Primary Examiner — Daniel J Domino*Assistant Examiner* — Ana M. Vine(74) *Attorney, Agent, or Firm* — Howard M. Gitten, Esq.; Lewis Brisbois Bisgaard & Smith LLP(57) **CLAIM**

The ornamental design for a data display screen with icon set, as shown and described.

DESCRIPTION

The sole FIGURE is a front view of a data display screen with icon set showing the new design.

The claimed design is directed to the collective appearance of the icon set shown in the drawing. The outermost broken lines illustrate a data display screen with icon set in which the design is embodied that form no part of the claimed design. The remaining broken lines illustrate portions of the graphical user interface that form no part of the claimed design.
